Specification for Design.

Patented Apr. 20, 1920.

Application filed November 13, 1919. Serial No. 337,855. Term of patent 7 years.

To all whom it may concern:

Be it known that I, WALTHER H. GROTE, a citizen of the United States, residing at Louisville, in the county of Jefferson and State of Kentucky, have invented a new, original, and ornamental Design for Tires, of which the following is a specification, reference being had to the accompanying drawing, forming part thereof.

Figure 1 is a plan view of a portion of a vehicle tire showing my design, and

Fig. 2 is a transverse sectional view through the same on the line 2—2 of Fig. 1.

I claim:—

The ornamental design for a tire, as shown.

WALTHER H. GROTE.
